(57) **CLAIM**

The ornamental design for a desk organizer, as shown and described.

DESCRIPTION

FIG. 1 is a front perspective view of a desk organizer showing the new design;

FIG. 2 is a front view thereof;

FIG. 3 is a back thereof;

FIG. 4 is a left side thereof;

FIG. 5 is a right view thereof;

FIG. 6 is a top thereof;

FIG. 7 is a bottom thereof; and,

FIG. 8 is a front perspective view thereof showing the swing out drawers in their open configuration.

The broken lines showing surfaces in the drawings are included for the purpose of showing portions of the desk organizer that form no part of the claimed design.

1 Claim, 8 Drawing Sheets
